UNITED STATES PATENT OFFICE.

RALPH S. ROBERTS AND CLARENCE E. WEXELBERG, OF DETROIT, MICHIGAN, ASSIGNORS TO BRIGGS MANUFACTURING COMPANY, OF DETROIT, MICHIGAN, A CORPORATION OF MICHIGAN.

DESIGN FOR AN AUTOMOBILE BODY FRONT UNIT.

Application filed November 28, 1927. Serial No. 24,323. Term of patent 7 years.

To all whom it may concern:

Be it known that we, RALPH S. ROBERTS and CLARENCE E. WEXELBERG, both citizens of the United States of America, residing at Detroit, in the county of Wayne and State of Michigan, have invented a certain new, original, and ornamental Design for an Automobile Body Front Unit, of which the following is a specification, reference being had therein to the accompanying drawings, forming part thereof, in which—

Fig. 1 is a top plan view of the automobile body front unit;

Fig. 2 is a side elevational view of the same; and Fig. 3 is a perspective view.

We claim:

The ornamental design for an automobile body front unit substantially as shown.

CLARENCE E. WEXELBERG.
RALPH S. ROBERTS.
